APPARATUS FOR CONVERTING HYDROCARBONS

Original Filed Sept. 11, 1930

Barry & Curr

UNITED STATES PATENT OFFICE

2,150,090

APPARATUS FOR CONVERTING HYDRO-CARBONS

Malcolm P. Youker, Bartlesville, Okla., assignor to Phillips Petroleum Company, Bartlesville, Okla., a corporation of Delaware

Original application September 11, 1930, Serial No. 481,318. Divided and this application September 9, 1935, Serial No. 39,839

5 Claims. (Cl. 196—10)

My invention relates to gas conversion processes, and more particularly to improvements in apparatus for converting normally gaseous hydrocarbons by a method of the kind disclosed in my

5 Patent No. 1,800,586, dated April 14, 1931. The present case is a division of my application Serial No. 481,318, filed September 11, 1930, (Patent No. 2,027,460, dated January 14, 1936) and the present application should be considered in conjunction with said Letters Patent, as Serial No. 481,318 is a continuation in part of the application which resulted in said patent.

In said Patent No. 1,800,586, there is disclosed a process of converting normally gaseous hydrocarbons into normally liquid hydrocarbons by first subjecting a stream of gaseous hydrocarbons to a temperature in excess of 750° F. while under a pressure in excess of 500 pounds per square inch, and after the conversion is effected in this way, the resulting mixture is fractionated to produce a fixed gas fraction, a gasoline fraction, and a third fraction intermediate between the fixed gas and gasoline fractions, the third fraction being recycled or processed in a similar treatment.

25 In the continuation in part application, Serial No. 481,318, I have disclosed and claimed improvements in said process, and in this divisional application, I lay claim to the apparatus described and illustrated in said continuation in part application.

The primary purpose of the present invention is to provide an apparatus having great flexibility in order that it may be used for converting hydrocarbon gases alone or mixtures of hydrocarbon gases and hydrocarbon liquids, with or without the recycling of gases and/or liquids produced in the process.

With the foregoing objects outlined and with other objects in view which will appear as the description proceeds, the invention consists in the novel features hereinafter described in detail, illustrated in the accompanying drawing, and more particularly pointed out in the appended claims.

The figure illustrates diagrammatically in side elevation, one form of apparatus including my improvements.

Referring to the drawing, 1 designates a furnace through which pipes or tubes, hereinafter referred to, are passed, for the purpose of heating fluids flowing through such conduits. 2, 3, 4, 5, 6 and 7 designate cylindrical closed vessels used for separating gases and/or vapors from liquids.

55 Pipe lines in which the condensation of materials

undergoing treatment takes place, are passed through condensers 8, 9, 10 and 11. Bubble trays 12 are disposed in rectifiers or fractionating columns 13 and 14, and in an absorber tower 15.

Hydrocarbon gases, in either liquid or vapor phase, will be introduced into the apparatus through a pipe line 16 in which is interposed a control valve 17, a pump 18, and a pressure reducing valve 19. The pipe line 16 extends through the furnace to the separator 2, and the parts 17 and 19 are positioned anterior to the furnace, while the pressure reducing valve 18 is located between the furnace and the separator for the purpose of reducing the pressure on the heated fluid before the latter enters the separating chamber.

Liquid collecting in the separator 2 is discharged through a line 20 leading to the medial portion of the first rectifying column 13. A control valve 21 is interposed in the pipe.

Liquid collecting at the bottom of the fractionating column will be discharged through a pipe 22 and a valve 23 into the fractionating column 14.

Liquid which will collect in the bottom of the column 14 can be discharged through a pipe 24 and a valve 25 into the separator 7, and liquid or tar accumulating in the latter will be discharged therefrom by a pump 26 through a pipe 27 and a cooler (not shown).

Vapors and permanent gases will separate from the liquid in the separator 2, and will be discharged by way of a pipe line 28, through condenser 8 and into the separator 3. Vapors and gases will pass from the top of column 13 by way of pipe 29 through condenser 9 into separator 4. 35 Vapors and gases will also pass from the top of fractionating column 14 by way of a pipe 30 through condenser 10 into separator 5. Vapors will pass from the top of separator 7 by way of pipe line 31 through condenser 11 into separator 6. 40

Gases, such as excess hydrogen, hydrogen sulfide, nitrogen and helium, separate from heavier gases and vapors in the separator 3, and are substantially constantly vented from the system through a pipe 32 in which is interposed a back pressure valve 33. Similar gases may be vented from the top of separator 4, through a pipe 34 provided with a back pressure valve 35.

If any such gases should remain with heavier materials when the latter reaches the separator 5, these gases may be vented through the pipe 36 and valve 37 arranged at the top of the separator 5.

For the purpose of maintaining sub-atmospheric pressure within the separator 6, a gas vent

55

pipe 38 is arranged at the top of this chamber, and is provided with a vacuum pump 39. This pump will also maintain sub-atmospheric pressure within the separator 7, as the pipe line 31 connecting these separators does not have any valves interposed therein.

Liquefied gases, heavier than hydrogen, hydrogen sulfide, nitrogen and helium, which accumulate in the bottom of separator 3 are forced by the pump 40 through a pipe line 41 and valve 84 into the pipe 16 at a point between the pump 19 and the furnace 1 for recycling purposes.

Liquid accumulating in the separator 4 can be delivered by a pump 42 through pipes 43 and 41 into the pipe 16 at a point between the pump 19 and the furnace.

Liquid or gasoline collecting in the bottom of separator 5 is delivered therefrom through a pipe 44 having a control valve 45.

20 Liquid accumulating in the bottom of separator 6 may be discharged by means of a pump 46 through a pipe 47 having a control valve 48.

If desired, some of the above mentioned fixed gases can be recycled from the top of the separator 3 by means of a pipe line 50 having a compressor 49 and a control valve 51 interposed therein.

A conduit 53 having a valve 52 interposed therein, connects the upper portion of the separator 2 to the pipe 50, so that the compressor 49 may be used to force gases and vapors from the separator into the pipe 16 at a point between the pump 19 and the furnace.

30 Gases from the top of the separator 4 can be introduced into the pipe line 50 posterior to the compressor 49 by means of a compressor 54 interposed in a pipe 55 having a control valve 56.

A reflux liquid can be delivered from the bottom of the separator 4 into the top of the rectifier 13 by means of a pump 57 interposed in the pipe 58, for the purpose of preventing gasoline and heavier materials from entering the pipe 29.

45 Liquid can also be delivered from the bottom of the separator 5 into the top of the rectifier 14 by means of a pump 59 interposed in a conduit 60 to prevent material heavier than gasoline entering the pipe 30.

For the purpose of heating the bottom of the column 13, a pump 61 is interposed in a pipe 62, extending from the bottom of the column 13 through the furnace and back into the lower portion of this column. A similar device, 63, 64, is employed for heating the bottom of the column 55 14.

A pipe 65 having a valve 66 leads from an extraneous supply of hydrocarbon liquid to a pump 67. Some or all of this hydrocarbon liquid can be forced by the pump 67 through a pipe 68 having a valve 69, into the pipe 16, at a point between the pump 19 and the furnace.

Another pipe 70 having a valve 71, leads from the outlet of the pump 67 into the top portion of the absorber 15, and a conduit 72 having a 65 valve 73 connects the bottom of the absorber to the pipe 16 at a point ahead of the pump 19.

Heavy oil, such as fuel oil or gas oil can thus be delivered directly into the pipe 16 posterior to the pump 19, or can be passed through the absorber into the pipe 16 at a point anterior to the pump 19.

70 Gas entering the pipe 16 can be introduced into the absorber through a pipe 74 having a valve 75, and some of the up-flowing gas can be absorbed by the heavy oil flowing downwardly

through the absorber, and then the mixture of oil and gas may be introduced into the pipe 16 through the pipe 72. Gases escaping absorption in the absorber 15 are discharged through a pipe 76 having a back pressure valve 77, the latter permitting the absorber to be operated under super-atmospheric pressure.

A hydrocarbon liquid, which may be a heavy oil, gas oil or crude oil, may be introduced into the pipe 16 at a point between the furnace and the separator 2, by means of a pump 80 interposed in a pipe line 78 having a control valve 79.

A pipe 81 in which are mounted valves 82, 83 and 91, connects into the pipe 78 on the suction side of the pump 80, and connects into the pipe 65 on the suction side of the pump 67 for the purpose of introducing liquid produced in the system into the pipe 16, either ahead or after the furnace, and also into the absorber 15. A pipe 85 having an interposed pump 86 and a valve 87 leads from the bottom of the rectifier 14 into pipe 81, and another pipe 88 provided with an interposed pump 89 and a valve 90 leads from the bottom of separator 6 to the pipe 81. Obviously, the pumps 86 and 89 can be used to deliver heavy oils from the rectifier 14 or the separator 6 into either the pipe 65 or pipe 78.

A pipe 92 having a valve 93 is connected to the pipe 85 at a point between the pump 86 and valve 87, so that liquid withdrawn from the bottom of the fractionating column 14 may be delivered to storage.

From the foregoing it will be apparent to those skilled in the art that gases may be introduced into the inlet of the heating tube 16 through the inlet end of this pipe, or by means of the pipes 41 or 50, or gas may be fed into the heating coil, absorbed in the oil by means of the pipe 72, or admixed with oil introduced from an extraneous source through pipe 65, or produced in the system and coming from the rectifier 14 or separator 6. Furthermore, a hydrocarbon liquid can be introduced into the pipe 16 by means of the pipe 78, either from an extraneous source or from the rectifier 14 or separator 6. Hence, a variety of operations can be carried out by the present apparatus, for the polymerization of gases, the cracking of oil, the distillation of oil, or for combinations of these operations.

In my parent application Serial No. 481,318, I have disclosed how hydrocarbon liquids may be made from hydrocarbon gases by two methods which are closely related, and both of which may be practiced in the present apparatus. These methods of gas conversion may be used separately or may be combined in the same process, and the apparatus disclosed may be used to carry out either one of these methods or the combination of the two. For the purposes of clarity, I will describe these methods separately.

Some of the hydrogen may be removed from hydrocarbon gases, and the remaining hydrogen content be simultaneously recombined with the carbon content of such gas to form liquid hydrocarbons, or carbon may be added to hydrocarbon gases and combined with excess hydrogen contained therein to form a hydrocarbon liquid. The former case would be de-hydrogenation of the hydrocarbon gases, and the latter case may be called carbonization of hydrocarbon gases.

70 My apparatus may be used to de-hydrogenate gas in the following manner:

Hydrocarbon gas in either liquid or gaseous state will be delivered by pump 19 through the pipe 16, and will be heated therein to a tempera- 75

ture preferably between 700 and 1000° F. while held under a pressure in excess of 500 pounds per square inch. I have found that good results may be obtained at a temperature around 875° F. under pressures between 2000 and 3000 pounds per square inch, and a good conversion from gases to liquids results. After the conversion of part of the gases to liquid has taken place in the pipe 16, cold hydrocarbon liquid is introduced into the pipe 16 through the pipe 78 in order to cool the mixture of gases and liquids down to such a temperature, say 400 to 600° F., that only gases which are more volatile than gasoline will remain in the vapor or gaseous phase; the cooled 10 converted gases and liquid, together with the added hydrocarbon liquid then flowing into separator 2. Gases and vapors which are more volatile than gasoline will then flow through pipe 28 and condenser 8 into separator 3. As the material passing through the condenser 8 will be cooled, a mixture of liquid and gas will be delivered into the separator 3. The material which remains in a gaseous state after passage through the condenser will be vented from the system 15 through the pipe 32. Some of it may be recycled if desired by means of the compressor 49.

Liquid collecting in the separator 3 can be withdrawn therefrom and recirculated through the pipe 16, and thereby through the process, by 20 means of pump 40.

Liquid trapped in separator 2 will, of course, consist mainly of gasoline and heavier hydrocarbons, but as only a rough separation takes place in this separator, it will also contain material 25 more volatile than gasoline, and this liquid will be delivered through the pipe 20 into the rectifier 13. The latter makes a relatively sharp separation between gasoline and heavier hydrocarbons on the one hand, and material lighter than gasoline on 30 the other hand, and this lighter material discharged through pipe 29, is cooled in the condenser 9, with the result that a mixture of liquid, gases, and vapors flows into the separator 4. Some of the liquid collecting in this separator is 35 forced by the pump 57 into the top of the column 13 for reflux purposes, with a view of preventing gasoline and heavier material from entering the pipe 29. Some of this liquid can also be recycled by means of pump 42 and pipes 43 and 41. Gases leaving the top of the separator 4 40 can be vented from the system through the pipe 34, or some of them may be recycled by means of compressor 54 and the pipes 55 and 50.

Liquid consisting of gasoline and heavier hydrocarbon material is discharged from the bottom of column 13 through the pipe 22, leading to the medial portion of the column 14, and 45 gases and vapors pass from the top of the latter column through the pipe 30 and condenser 10 into the separator 5 where the gasoline is accumulated. Any gases remaining uncondensed are discharged from the separator 5 through the pipe 36. Some of the gasoline accumulated in the separator 5 is forced by the pump 59 into the top 50 of the column 14 for reflux purposes, so that hydrocarbon material heavier than gasoline is prevented from entering the pipe 30. Gasoline is withdrawn from the system through the pipe 44.

Liquid which is heavier than gasoline, that is, 55 fuel oil and gas oil, may be withdrawn from the bottom of column 14 through the pipe 92 to storage, or some or all of it may be recycled by means of the pump 86.

The vacuum distillation unit, consisting of the 60 separators 7 and 6, condenser 11 and accessory

pumps, pipe lines, etc., is conventional and is for the purpose of separating gas oil or lubricating oil from fuel oil, and as before stated, gas oil accumulating in the bottom of the separator 6 may be recirculated by means of the pump 89 to either 5 the pipe 16 or pipe 78.

Through manipulation of valves 18, 21 and 33, superatmospheric pressure, say to 2000 to 3000 pounds per square inch may be maintained in the separators 2 and 3, and in the pipe lines accessory to these separators. By manipulating valves 23 and 35, pressure preferably between 400 10 to 700 pounds per square inch, sufficiently high to condense in condenser 9 all vapors passing through pipe 28, will be maintained in the column 13, separator 4 and accessory pipe lines. By means of the valve 37, atmospheric pressure will 15 preferably be maintained in the column 14, separator 5 and connecting pipe lines.

By the method of operation just described, 20 natural gas or constituents of natural gas may be charged to the apparatus through the pipe 16, and a portion of the same will be converted into synthetic crude oils and gases. The apparatus is so designed that after conversion has taken 25 place, the converted material may be separated into the following fractions: Permanent gases, some of which are vented from the system through the pipes 32, 34 and 36, and some of which may be recycled by means of compressors 30 49, 54 or both; gases which are heavier than said permanent gases, but more volatile than gasoline, and which may be recycled by means of pumps 40, 42; motor fuel or gasoline discharged through the pipe 44; and heavier oils, such as gas oil or 35 fuel oil which may be withdrawn from the system through pipes 92 and 47, or which may be recycled by means of pumps 86 and 89.

Gas delivered to the apparatus ordinarily contains certain permanent gases which, if not vented from the system, would, in a short time, fill the system and prevent the apparatus from operating. Hydrogen is also continuously evolved within the system, and if such gases are not vented from the apparatus, they will interfere with the 40 operation. For this reason, I have provided the vent pipes 32, 34 and 36 for substantially constantly venting such gases from the system.

Furthermore, by means of my apparatus, the material produced which is heavier than these permanent gases and more volatile than gasoline, may be readily recycled, as they are maintained under high pressure at all times, and preferably in liquid form in order that the recirculation may be accomplished economically. When gas only 50 is supplied from an extraneous source to the apparatus, a considerable quantity of hydrogen will necessarily be vented from the system.

If it is desired to simultaneously treat hydrocarbon gases and hydrocarbon liquids, fuel oil 60 or gas oil may be introduced into the pipe 16 from the various sources heretofore referred to, to supply carbon with which to combine the excess hydrogen contained in the gas, in which case hydrogen need not be vented from the system, and only such permanent gases as are inadvertently introduced into the system with the charging stock will be separated from the other materials and vented from the system. Liquids which contain a higher percentage of carbon than 65 70 is contained in gasoline, can, of course, be introduced into the system either through the pipe 65 or pipe 78. In the event that crude oil should be introduced, it is passed through the pipe 78, and the gasoline content in this oil will be dis- 75

tilled therefrom, due to the admixture of the oil with the heated material from the pipe heater, and such gasoline will be separated from the other products in the fractionating system. Of course, the gas oil and fuel oil contained in such crude oil will again enter the pipe 16 as a recirculated liquid, coming either from column 14 or separator 6. This is an indirect way of introducing fuel oil or gas oil into the system when crude oil only is available for the purpose.

It has been found desirable in some cases to cool any liquid which is heavier than gasoline, and which is introduced into the pipe 16, and to initially use this heavy oil as an absorbent to absorb constituents of natural gas, and subsequently introduce the mixture of heavier than gasoline liquids and lighter than gasoline constituents thus produced into the pipe 16. Obviously, the absorber 15, with inter-connecting lines shown, may be used for this purpose.

As stated in my Patent No. 1,800,586, and parent application Serial No. 481,318, I do not propose to limit the present apparatus to the treatment of natural gas, but may use it to convert other hydrocarbon gases such as those produced by the cracking of heavy oils, and the treatment of other carbonaceous materials. In some cases, I will, in the manner described herein, use the apparatus to add carbon contained in heavy oils, such as fuel oil or gas oil, to hydrocarbon gases resulting from cracking natural gas under comparatively low pressures and high temperatures.

While I have disclosed what I consider to be a preferred embodiment of the invention in such manner that the same may be readily understood by those skilled in the art, it is manifest that changes may be made in the details disclosed, without departing from the spirit of the invention, as expressed in the claims.

40 What I claim and desire to secure by Letters Patent is:

1. In an apparatus of the character described, a furnace, a heating tube for conveying a stream of hydrocarbons through the furnace, a first separator connected to the outlet end of said tube and in which gases and vapors separate from liquid, a second separator for separating lighter gases from heavier ones, a first pipe leading from the top of the first separator to the second separator, means for cooling gaseous material flowing through the pipe for condensing a portion of said material before the latter flows into the second separator, valve controlled means for venting uncondensed material from the top of the second separator, means for returning condensate from the second separator to the intake of the heating tube, a rectifying column, a pipe for leading liquids from the bottom of the first mentioned separating chamber into the medial portion of the rectifying column, means for heating the bottom portion of the rectifying column, a conduit for discharging gaseous material from the top of the rectifying column, a third separator receiving the material from said conduit, a cooler for cooling said material as it flows through the conduit for condensing a portion of said material before it enters the third separator, means for returning a portion of the last mentioned condensate into the top of the rectifying column for reflux purposes, means for returning another portion of said last mentioned condensate to the intake of the heating tube and means for withdrawing liquid hydrocarbons from the rectifying column.

2. In an apparatus of the character described, a furnace, a heating tube for conveying a stream

of hydrocarbons through the furnace, a first separator connected to the outlet of said tube and in which gases and vapors separate from liquid, a second separator for separating lighter gases from heavier ones, a first pipe connecting the top portion of the first separator to the second separator for conveying gases and vapors from the first separator to the second separator, means for cooling the last mentioned gases and vapors as they flow through the pipe for condensing a portion of these materials before they flow into the second separator, valve controlled means connected to the top of the second separator for venting uncondensed gases from the top of the second separator, a second pipe provided with an interposed compressor and valve connecting said valve controlled means to the inlet of the heating tube for recycling some of said uncondensed gases, a third pipe connected to the bottom portion of the second separator for withdrawing condensate from said second separator, and a fourth pipe connected to the bottom portion of the first separator for discharging liquids from the latter, a valve controlled conduit connecting the upper portion of the first separator to the second pipe anterior to the compressor of the latter for returning gases and vapors directly to the intake of the heating tube without passing them through said cooling means and second separator.

3. In an apparatus of the character described, a furnace, a heating tube extending through the furnace, a separator connected to the outlet end of said tube and in which gases and vapors separate from liquid, means for discharging gases and vapors from the upper portion of said separator, a rectifying column, a pipe connecting the lower portion of the separator to the medial portion of the rectifying column, means for feeding liquid from the lower portion of the rectifying column in a confined stream through the furnace and back into said rectifying column, another separator, a conduit connecting the upper portion of the rectifying column to the last mentioned separator and having a condenser interposed therein for feeding a mixture of vapors and gases from the rectifying column and for condensing a portion of the same before discharging the mixture into the last mentioned separator, a pipe connecting the lower portion of the last mentioned separator to the top portion of the rectifying column for returning some of said condensate into the rectifying column for reflux purposes, a valved vent pipe leading from the top of the last mentioned separator for discharging normally gaseous material from the last mentioned separator, fluid conveying means connecting the vent pipe to the inlet end of the heating tube, and a liquid discharge pipe leading from the bottom portion of the rectifying column.

4. In an apparatus of the character described, a furnace having a heating tube therein for conveying a stream of hydrocarbons therethrough, a first separator connected to the outlet end of said heating tube to receive the effluents therefrom and for separating gases and vapors from liquids, a second separator for separating light gases from heavy gases, a pipe connecting said separators, a condenser interposed in said pipe for cooling and condensing a portion of the gases flowing therethrough to said second separator, a pipe connecting said second separator with the intake of said heating tube for returning condensate thereto from said second separator, a valve controlled pipe leading from said second separator for venting uncondensed gases therefrom, a rectifying

column having a pipe connecting a medial portion thereof with said first separator for conducting liquids therefrom to said rectifying column, a pipe leading from the bottom of said rectifying column through said furnace and back into said column to heat the bottom portion thereof, a third separator, a valve controlled pipe leading from said third separator for venting uncondensed gases therefrom, a pipe connecting the third separator with the top of said rectifying column for the discharge of gaseous material therefrom, a condenser interposed in the last mentioned pipe for cooling and condensing a portion of said gaseous material, a pipe connecting the bottom of said third separator with the top portion of said rectifying column for the introduction therein of reflux condensate from said third separator, a pipe connecting said third separator with the intake of said heating tube for returning condensate thereto from said third separator and a pipe for withdrawing liquid hydrocarbons from said rectifying column.

5. In an apparatus of the character described, a furnace, a heating tube for conveying a stream of hydrocarbons through the furnace, means for forcing normally gaseous hydrocarbons into the inlet end of said tube, separate means for forcing a normal liquid hydrocarbon into the inlet end

of said tube, a first separator connected to the outlet of said tube and in which gases and vapors separate from liquid, a second separator for separating lighter gases from heavier ones, a first pipe connecting the top portion of the first separator to the second separator for conveying gases and vapors from the first separator to the second separator, means for cooling the last-mentioned gases and vapors as they flow through the pipe for condensing a portion of these materials before they flow into the second separator, valve controlled means connected to the top of the second separator for venting uncondensed gases from the top of the second separator, a second pipe provided with an interposed compressor and valve, connecting the top portion of the second separator to the inlet of the heating tube for recycling some of said uncondensed gases, a third pipe connected to the lower portion of the second separator and leading to the inlet of the heating tube for conveying condensate from the second separator to the inlet of the heating tube, means interposed in the third pipe for forcing condensate therethrough, and a valve interposed in the third pipe for controlling the flow of condensate therethrough.

MALCOLM P. YOUNKER.
